Doyle C. Warren, Monrovia, Calif., assignor to Chiksan Company, Brea, Calif., a corporation of California

Application June 1, 1948, Serial No. 146,710

Term of patent 14 years

(Cl. D91—1)

To all whom it may concern:

Be it known that I, Doyle C. Warren, a citizen of the United States, residing in the city of Monrovia, county of Los Angeles, and State of California, have invented a new, original, and ornamental Design for an Oil Well Casing Head, of which the following is a specification, reference being had to the accompanying drawings, forming a part thereof.

Fig. 1 is a perspective view of an oil well casing head, showing my new design, as viewed from the top and one side, and Fig. 2 is a side elevational view of the oil well casing head as viewed from the other side thereof.

I claim:

The ornamental design for an oil well casing head, as shown.

DOYLE C. WARREN.
